[57] **CLAIM**

The ornamental design for a trash can with lid, as shown and described.

DESCRIPTION

FIG. 1 is a front elevational view of a trash can and lid with a portion removed illustrating my design;

FIG. 2 is a top plan view of FIG. 1 with the lid removed;

FIG. 3 is a perspective view, slightly reduced in size, of FIG. 1 with the lid displaced vertically; and

FIG. 4 is an enlarged partial sectional view taken along line 4—4 of FIG. 1 illustrating the interlocking lid and trash can.

The bottom view is plain and unornamented except for the side indentations shown in FIGS. 1, 2, and 3.
